Primary Examiner — Manpreet Matharu*Assistant Examiner* — Suzanne Tisdell(74) *Attorney, Agent, or Firm* — Innovation Capital Law Group, LLP; Vic Lin(57) **CLAIM**

We claim the ornamental design for the shed, as shown and described.

DESCRIPTION

FIG. 1 is a top front perspective view of a shed;
 FIG. 2 is a top rear perspective view thereof;
 FIG. 3 is a front elevation view thereof;
 FIG. 4 is a rear elevation view thereof;
 FIG. 5 is a right elevation view thereof;
 FIG. 6 is a left elevation view thereof; and,
 FIG. 7 is a top plan view thereof.
 Features shown in broken lines show environmental subject matter and form no part of the claimed design.
